United States Patent Office.

WILLIAM CHESLEY, OF CINCINNATI, OHIO.

Letters Patent No. 95,323, dated September 28, 1869.

IMPROVEMENT IN STEAM-GAUGES.

The Schedule referred to in these Letters Patent and making part of the same.

To whom it may concern:

Be it known that I, WILLIAM CHESLEY, of Cincinnati, in the county of Hamilton, and State of Ohio, have invented a new and useful Improvement in Steam-Gauges; and I hereby declare the following to be a full, clear, and exact description thereof, reference being had to the accompanying drawings, making a part of this specification.

This is an improvement in the class of devices in which a convoluted disk of steel, technically known as the spring-disk, (in contradistinction to the metallic diaphragms, used in conjunction with spiral springs,) is employed to indicate the pressure of steam, or other confined gas, and relates, first, to a form and arrangement of the margin of the diaphragms and of the gripping-surfaces of the containing-head or chamber, which combine great security, efficiency, and compactness with economy of labor and material; and secondly, to a device for regulating the dial-works, so as to correct either too long or too short a range of the needle.

Figure 1 is an axial section of a steam-gauge embodying my improvements.

Figure 2 is a perspective view of several members of the same detached.

Figure 3 is a section taken in the plane of my setting or adjusting-screws.

A represents the base or cup of my confining-head, or chamber, and B, the cap or crown thereof.

These two members have heretofore been always either both of brass or some other one metal, but for an advantage purely incidental to my construction, and which will presently appear, I prefer to make my base of cast-iron, and my cap of brass or bell-metal.

The base A terminates at the bottom in a customary screw-threaded neck, C, for attachment to a pipe emanating from the boiler, or another receptacle, and at the top in an annular ridge or boss, D; having a peripheral recess, d, to receive the marginal lip F of a spring-disk, E, which lip is securely gripped at every part between the concavity G, of my cap B, and said recessed periphery D.

The rubber shield or gasket H, where one is used, is of corresponding diameter to the boss D, and is tightly gripped between the top of the boss and the under side of the diaphragm.

It will be seen that I dispense entirely with the wide marginal extensions in general use hitherto, for all spring-disks employed without spiral or other auxiliary springs, which extend to the outside of the common flanges of the base and cap respectively, and which also, like them, are required to be pierced with six or more holes, for the passage of as many bolts.

These bolts, twenty-four to thirty-two in number,

to wit, six to eight in each of the above-recited members, I entirely dispense with, by the provision of the recessed boss D and lip F, in connection with the described concavity G, and the corresponding screw-threaded surfaces I J, on the periphery of the base and the concavity of the cap respectively; the annular interval afforded by the recess D, being of sufficient width and thickness to contain and firmly grip at every part of the marginal rim of the disk in the act of screwing down the cap.

K is the customary screw-neck for attachment of the dial.

In order to prevent any disturbance of the disk and gasket by the screwing on of the cap, I provide a ring L, which I call the nipping-ring, flat on its under and convex on its upper side, its preponderating lower surface enabling it to remain stationary upon the spring-disk, and yet allow the cap, in rotating, to glide easily over it.

L' is the dial-plate, of customary form, screwed on to the cap of the diaphragm-chamber, to which plate, or to a suitable frame, M, attached thereto, is journaled the usual pinion N, to whose shaft and to said frame are attached the extremities of the customary spiral spring O.

Journalled at P', within the frame M, so as to gear with said pinion, is a segmental rack, P, having a heel from which rises a stud, Q, that traverses a plate, R, having a hinge-joint or connection, S, with a rod, T, of customary form, whose lower end is swivelled to a stud, U, which rises from the spring-diaphragm.

Tapped within the heel P', are two setting-screws, V V', which bear upon opposite sides of the heel of the plate R, and being one or another of them advanced, serve to press the joint S nearer to or further from the journal P', so as to increase or diminish the sweep of the rack with a given deflection of the spring-diaphragm.

These screws afford a very simple means of graduating the indicating-mechanism while the gauge is in operation, with great accuracy, and without liability to derangement.

Among a number of benefits of my invention the following may be cited:

The lip F serves to hold the spring-dial much more securely and evenly than do the common bolts and flanges, and is much more easily and effectually applied than if it entered in a groove, which form I do not claim.

Incident to my mode of securing the downturned rim between the concavity of the cap and the recessed boss of the base, are several very decided practical advantages:

For example, the rim, even though it should not

actually fit the parts, is readily and effectually strained to a complete and equal bearing all around, by the mere act of screwing down the cap.

A spring-disk, not exceeding two-thirds of the area of that customarily employed, is available with the same effective area and play.

The labor and expense are avoided of gripping the flanges of the head six or more times, and drilling as many holes, tapping the six or more holes of the base, and providing as many bolts.

The head is much lighter and cheaper, and of more compact and elegant appearance.

By making the base of iron, and the cap of brass, the latter is, in consequence of its greater expansibility, rendered easily detachable from the former on being heated. The iron base is also more secure against leakage, being less subject to blow-holes than brass.

The nipping-ring or washer having a preponderating lower surface to hold the spring, enables the cap to be screwed with any desired force, without shifting or disturbing the spring.

A gasket, of copper or other soft infusible material, may be introduced between the diaphragm E and the nipping-ring, or even substituted for the latter; and said ring may be of any form that will afford a preponderating lower surface.

While preferring iron and brass for the base and cap

respectively, I claim the right to use any two metals whose relative thermal expansibility shall be such as to effect the object stated.

I am aware that steam-pressure gauges have been proposed, having metallic rimless diaphragms supported on their convex sides by spiral springs, and whose edges have been secured by the simple screwing together of a cap and base, and therefore make no claim to such, broadly; nor do I claim the provision of a marginal flange to a spring-disk, except when nipped or secured between the annular and recessed boss of the base, and the concavity of a cap screwing down upon said base, in the manner herein represented.

I claim herein as new, and of my invention—

1. The construction of the spring-disk of a steam-pressure gauge, with the circumferential rim or flange F, for the purpose set forth.

2. The oscillating segment-rack whose jointed connection with the spring-disk or diaphragm is made adjustable by means of the vibratable plate R, and conical-necked setting-screws, substantially as and for the purpose set forth.

In testimony of which invention, I hereunto set my hand.

WILLIAM CHESLEY.
